UNITED STATES PATENT OFFICE

157,883

TOOL HANDLE

Elmer D. Maxwell, Booneville, Miss.

Application February 23, 1949, Serial No. 1,011

Term of patent 14 years

(Cl. D93—4)

To all whom it may concern:

Be it known that I, Elmer D. Maxwell, a citizen of the United States of America, residing at Booneville, in the county of Prentiss and State of Mississippi, have invented a new, original, and ornamental Design for a Tool Handle, of which the following is a specification, reference being had to the accompanying drawing, forming part thereof.

Figure 1 is a side elevational view of a tool handle, showing my new design.

Fig. 2 is a bottom plan view.

Fig. 3 is a sectional view taken on line 3—3 of Fig. 1.

Fig. 4 is a sectional view taken on line 4—4 of Fig. 1.

I claim:

The ornamental design for a tool handle, as shown and described.

ELMER D. MAXWELL.
